UNITED STATES PATENT OFFICE

2,225,010

INK APPLICATOR

Joseph Jetté, Fall River, Mass.

Application September 8, 1939, Serial No. 294,007

4 Claims. (Cl. 91—62.5)

This invention relates to an ink applicator especially adapted for applying ink to a glass for the making of finger-prints, and has for the primary object the provision of a device of this character which will contain a supply of ink used in the making of finger-prints and a means for discharging the ink on the glass as desired and a roller for distributing the deposited ink over a selected portion of the surface of the glass without the hands and fingers of the operator coming in contact with the ink and becoming soiled thereby.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a side elevation illustrating an ink applicator constructed in accordance with my invention and showing the same at rest on a support.

Figure 2 is a side elevation of the applicator showing the device positioned for the depositing of ink on a surface.

Figure 3 is a side elevation illustrating the ink applicator positioned for the spreading of the ink on the surface.

Figure 4 is a longitudinal sectional view illustrating the ink reservoir of the applicator and the means of placing the ink under pressure within the reservoir.

Figure 5 is a fragmentary vertical sectional view illustrating the control means or valve for the release of the ink as needed.

Referring in detail to the drawings, the numeral 5 indicates a frame consisting of parallel arms 6 and a connecting portion 7. An axle or shaft 8 is journaled in openings provided in the arms 6 adjacent the free ends of the latter and has mounted thereon a roller 9 constructed of rubber or any other material suitable for the purpose.

A handle 10 is formed on the connecting member 7 intermediate the ends of the latter and is of hollow formation to provide an ink reservoir 11. The reservoir opens outwardly through the free end of the handle as well as opening outwardly through the connecting member 7 of the frame. The free end of the handle is reduced and screw threaded to be received within a cap 12. A gasket 13 is arranged in a recess within the free end of the handle to engage the cap

for sealing the latter onto the handle to prevent leakage of ink between the handle and cap. The cap 12 is provided with a recess 14 which communicates with the reservoir 11 and seated in the recess is a coil spring 15, one end of which is in the form of a shank 16 and has secured thereto a piston-like member 17 equipped with a suitable washer 18 that has frictional contact with the walls of the reservoir. The spring 15 is of the expandable type for the purpose of placing the ink in the reservoir under pressure.

The end of the reservoir 11 which opens outwardly through the connecting member 7 of the frame 5 is connected with a pipe or tube 19 and the latter connects with a cylinder 20 above the lower end thereof and also acts as a support or attaching medium for the cylinder onto the frame 5. The upper end of the cylinder is closed by a removable cap 21 through which operates a stem 22 of a plunger type valve 23. The plunger type valve is spring influenced by a coil spring 24 mounted on the stem between the plunger type valve and the cap 21 and normally acts to position the plunger type valve to close the pipe or tube 19 to the cylinder.

An operating lever 25 having a thumb piece 26 is pivotally mounted on a post 27 carried by the handle adjacent the frame and has a pin and slot connection, as shown at 28, with the stem of the plunger type valve so that by pressing on the thumb piece 26 the plunger type valve will be made to move to open the tube or pipe 19 to the cylinder for the purpose of allowing the ink to flow into the cylinder in a desired amount. As soon as pressure is released on the thumb piece 26, the spring 24 acts to restore the valve in a position to close the pipe or tube 19 to the cylinder and consequently cut off the flow of ink to said cylinder.

A pair of legs 29 is formed on the frame 5 or the connecting member 7 thereof and coact with the handle in supporting the device on a surface, as shown in Figure 1, with the lower end of the cylinder and the roller spaced from said surface. By lifting the handle upwardly the frame will fulcrum on the legs bringing the cylinder into engagement with the surface with the roller still spaced from said surface. Ink may then be applied to the surface by pressing on the thumb piece, the ink flowing from the lower end of the cylinder onto a restricted area of the surface. By lifting the handle upwardly to a greater degree, the roller contacts the surface and the cylinder moves away from said surface so that the roller then may be moved over the ink and

surface for the purpose of distributing the ink on the surface.

It is believed that the foregoing description, when taken in connection with the drawings, will 5 fully set forth the construction and advantages of this invention to those skilled in the art to which such a device relates, so that further detailed description will not be required.

Having thus described my invention, what I 10 claim is:

1. An ink applicator comprising a frame, a handle providing an ink reservoir carried by said frame, a fulcrum means on said frame and coactive with the handle for the support of the 15 frame on a surface whereby the elevation of the handle will pivot the frame towards the surface, ink dispensing means connected with the handle for discharge of ink on the surface after a movement of the frame towards the surface, and 20 means on said frame for spreading the ink on the surface by a further movement of the frame towards the surface and parallel to said surface.

2. An ink applicator comprising a frame, a handle providing an ink reservoir carried by said 25 frame and located at one end of the latter, a fulcrum means on said latter-named end of the frame and coactive with the handle for the support of the frame on a surface whereby the elevation of the handle will pivot the frame towards 30 the surface, ink dispensing means connected to the handle for discharge of ink onto the surface forwardly of the fulcrum means and after a movement of the frame towards said surface, and means on said frame for spreading the ink on the surface by further movement of the frame to-

wards the surface and parallel with said surface.

3. An ink applicator comprising a frame, a handle providing an ink reservoir carried by said frame and located at one end of the latter, a fulcrum means on said latter-named end of the frame and coactive with the handle for the support of the frame on a surface whereby the elevation of the handle will pivot the frame towards the surface, ink dispensing means connected to the handle for discharge of ink onto the surface 10 forwardly of the fulcrum means and after a movement of the frame towards said surface, and a roller journaled on the other end of the frame for spreading ink on the surface by a further movement of the frame towards the surface and 15 parallel with said surface.

4. An ink applicator comprising a frame, a handle providing an ink reservoir carried by said frame and located at one end of the latter, a fulcrum means on said last-mentioned end of the frame and coactive with the handle for the support of the frame on a surface whereby the elevation of the handle will pivot the frame towards the surface, a tube connected to the handle and terminating at an opposite side of the fulcrum from the handle, a manually controlled valve, ink dispensing means connected with the free end of the tube for the discharge of ink onto the surface after a movement of the frame towards said surface, and a roller journaled on the frame adjacent said ink dispensing means for spreading ink on the surface by a further movement of the frame towards the surface and parallel with said surface.

JOSEPH JETTE.
